(57) **CLAIM**

The ornamental design for an equipment cover, substantially as shown and described.

DESCRIPTION

FIG. 1 is a perspective view of an equipment cover showing my design; the broken lines showing of environment are for illustrative purposes only and form no part of my claimed design; and,

FIGS. 2-6 are respectively left, front, right, top, and bottom elevation views of the version of the cover shown in FIG. 1 in its normal orientation.
